CLAIM

The ornamental design for a surgical gown, as shown and described.

DESCRIPTION

FIG. 1 is a front view showing my new design for a surgical gown;

FIG. 2 is a rear view of the surgical gown of FIG. 1;

FIG. 3 is a left side view of the surgical gown of FIG. 1;

FIG. 4 is a right side view of the surgical gown of FIG. 1;

FIG. 5 is a front view showing the surgical gown of FIG. 1 expanded; and,

FIG. 6 is a perspective view showing the surgical gown of FIG. 1 being worn by a person.

The dashed lines are for illustrative purposes only and form no part of the claimed design.
